ABSTRACT OF THE DISCLOSURE

An open-ended casing on a support has a pair of conduits for fluid coolant around it opening into it. A tubular open-ended mold liner in the casing has a tubular baffle member around it with a space between. The ends of the mold liner open through caps on the ends of the casing and the baffle member is supported in the casing, with its ends spaced from the caps, by a flange around its outer wall extending outward and resting on a flange that projects inward from around the casing wall between the conduits. The flanges also separate the interior of the casing into two chambers so that fluid entering one chamber from one of the conduits circulates through the space between the baffle member and mold liner into the other chamber, and then out the other conduit. This structure enables the mold liner and baffle member to be readily replaced in the casing.

The present invention relates to molds for the continuous casting of metal. In particular, it is a continuous-casting mold assembly that incorporates means for circulating a fluid coolant through it and that has novel structure enabling the mold liner and other elements of the assembly to be replaced simply and quickly.

In the usual methods for the continuous casting of metals, molten metal is poured into an open-ended mold that chills and solidifies the periphery of metal to define a strand which is withdrawn continuously from the bottom of the mold as molten metal is poured in the top. If the mold gets too hot it will not chill the metal sufficiently to form a strand, therefore, in order to be able to work the method on a continuous basis, the interior of the mold must be continuously cooled to keep it below a certain maximum temperature. Moreover, the entire circumferential surface of the interior of the mold must be uniformly below such minimum temperature. If a portion of the mold surface is not sufficiently cooled, the periphery of the metal may not solidify at all at that point so that metal from the still-molten core of the strand will spill out as the strand is drawn from the mold, or the insufficiently cooled portion may only solidify a relatively thin skin which the heat of the molten core might remelt and let molten metal spill out.

It is customary to cool the mold by circulating a fluid coolant, usually water, around the outside of the mold liner, which defines the passage through which the metal passes to be formed into a strand. In the usual structure, a water jacket is attached around the mold liner. The jacket is connected to an outside supply of water, or other fluid coolant, by suitable inlet and outlet conduits so that fluid can be flowed continuously through it. Inside the jacket various conduits and baffles are provided to circulate the fluid around the mold liner as effectively as possible for maintaining the temperature of all portions of the circumference of the liner uniformly below a certain maximum.

In known constructions the water jacket and mold liner are incorporated in a unit that must be replaced as a whole in the continuous-casting machine, in order to replace a worn mold liner or to substitute one of a different size or configuration. This usually involves dis-

2

connecting the fluid supply hoses, in addition to having to loosen the connections by which the unit is mounted on the machine. In short, it is a bothersome procedure to have to remove the entire jacket and mold unit.

It is an object of the present invention to provide a continuous-casting mold assembly having a cooling system incorporated therein, in which the mold liner, and the baffle member which forms an important part of the assembly, are adapted to be removed easily from the rest of the assembly without having to detach the latter from the casting machine.

Another object is to provide an assembly as aforesaid, in which a mold liner and/or baffle member of a different size or configuration can be readily substituted.

A further object is to provide such an assembly, in which a uniform space is provided between the sides of the mold liner and an encircling baffle member for cooling fluid to flow around all sides of the mold liner at an equal rate so as to ensure uniform cooling of the walls of the mold liner, and in which said uniform space is established automatically when the mold liner is removed and replaced.

These objects are accomplished by the mold assembly of the present invention wherein an open-ended mold liner is supported in a casing by caps, which are over the ends of the casing with the ends of the mold liner opening through the caps. The casing, which is mounted on a support attached to the casting machine, has conduits around it opening into the interior of the casing, and a coolant, such as water, from an outside supply, flows into one of the conduits through an inlet passage in the support and flows out of the other conduit through an outlet passage in the support. A tubular baffle member around the mold liner is larger in diameter than the liner so as to provide a space between and the width of this space is made equal around the circumference of the liner by spacing fins at intervals around the inside of the baffle member. The baffle member is shorter than the interior of the casing between the caps and is supported in position with its ends spaced from the caps by a flange projecting outward from around its outer wall and resting on a flange projecting inward from the portion of the interior wall of the casing between the conduits. These flanges also serve to separate the interior of the casing into two chambers so that fluid flowing into one of the chambers from outside circulates through the space between the baffle member and the mold liner, into the other chamber, and then out through the other conduit.

The mold liner is readily extracted from the casing by removing one or both caps and lifting it out; the baffle member can also be lifted out when the mold liner has been removed. Thus the mold liner and baffle member are easily removed for replacement without having to remove the casing from the support or disconnect the fluid supply. Moreover, since the baffle member is not attached, but "floats" in the casing, and is located in position around the mold liner by the spacer fins on the baffle member, the critical space between the mold liner and baffle member is automatically adjusted to uniformity around the mold liner by the insertion of the mold liner into the interior of the baffle member in the casing when the mold liner is replaced.

Further objects, advantages and features of this invention will be apparent in the following description of illustrative embodiments depicted in the accompanying drawings wherein:

FIG. 1 is a vertical section through a continuous casting mold assembly embodying the invention;

FIG. 2 is a section along the line 2—2 of FIG. 1; and

FIG. 3 is a vertical section through a central portion of a mold assembly generally similar to the assembly

shown in FIG. 1, but having a curved mold liner and baffle member.

Referring to the drawings, the mold assembly of this invention includes an open-end casing 10 attached on a support 11 and having a mold liner 12 carried therein to be axially aligned between the outlet of a tundish, indicated by arrow 13 above it, and a supporting passageway for a strand of metal issuing from the mold, indicated by arrow 14 below. The support 11 is suitably mounted on the frame or other portion of a continuous-casting machine, but means for mounting the support is not shown since it forms no part of the present invention and consists of conventional structure.

A pair of conduits 15 and 16 attached to the casing extend respectively around upper and lower portions of the casing and have a plurality of openings 17 and 18 into the interior of the casing, and ports 19 and 20 opening outside the casing in fluid flow communication with passages 21 and 22 that are in the support 11. From the ports 19 and 20 the passages 21 and 22 extend through the support 11 to the other side where they are connected respectively to hoses 23 and 24 by means of conventional connector fittings indicated at 25 and 26. The conduit 16 is an inlet and the conduit 15 is an outlet and, as indicated by arrows in the drawing, a fluid coolant, such as water, from a supply not shown, flows from the hose 24, through passage 22 and conduit 16 into the interior of the casing. After it is circulated in the casing for cooling the mold liner 12 (by structure, subsequently described), the fluid passes out of the casing, through conduits 15 and passage 21 into the hose 23, which carries it off, either to be dumped or to be cooled and recirculated.

The mold liner 12, which is conventionally a copper tube, is supported in the casing 10 by caps 28 and 29 attached over the respective open ends of the casing by bolts 30. The ends of the mold liner 12 open through the caps 28 and 29 with one end of the mold liner secured in an appropriate opening in one of the caps and its other end fitting through an opening in the other cap. As shown in the drawing, the upper end of the mold liner 12 is attached in an opening 31 in the top cap 28. Its lower end is fitted through an opening 32 in the lower cap 29 so as to be removable therefrom and a sealing ring 33 is provided in the wall of opening 32 to make a leak-tight connection with the periphery of the mold liner. The mold liner 12 is therefore readily removed from the casing 10 by loosening the bolts 30 that hold the cap 28, and lifting the cap up to withdraw the mold liner, which is attached to the cap, up out of the casing. Thus the mold liner is easily replaced. If it is desired to substitute a mold liner of a different size or configuration, both caps 28 and 29 are removed and replaced by different caps that have openings corresponding to the different size or configuration.

Within the casing 10 fluid is circulated along the mold liner 12 by a tubular baffle 35 around the liner, the inside diameter of the baffle being larger than the outside diameter of the mold liner to provide a space 36 between. Short spacing fins 37 placed at intervals around the inside surface of the baffle 35 and bearing against the mold liner center the baffle around the liner to make the space 36 the same width all the way around.

The baffle 35 is shorter than the length of the interior of the casing 10 and is supported therein by a flange 38 projecting outward from around the outside of the baffle and extending over, and resting on, a flange 39 that projects inward from around the inside wall of the casing between the conduits 15 and 16. As shown, the outer edge of the flange 38 on the baffle has a down-turned edge 40 that rests on a flat seal ring 41 seated in an appropriate groove in the upper face of the flange 39. The baffle 35 is held in position in the casing by fins 46 attached on the outer wall of the baffle at intervals spaced around it. At their upper ends, the fins 46 project above

the top of the baffle and bear against the underside of the cap 28 so as to press the edge 40 of the flange 38 on the baffle firmly down against the seal ring 41 on the casing flange 39 to form a tight seal. The flanges 38 and 39 thus cooperate to separate the interior of the casing into two chambers, 42 and 43, around the baffle in the upper and lower portions, respectively, of the casing. In addition, the flanges 38 and 39 are located so that they support the baffle up in the casing to provide a space at each end of the baffle between the end of the baffle and the inside surface of the adjacent cap, 28 or 29. These spaces are designated 44 and 45 in FIG. 1.

The above-described structure and manner of mounting the baffle 35 in the casing enables the baffle to be easily removed for repair or replacement, when the mold liner is removed from the casing 10. Also, as best seen in FIG. 1, the flange 39 projects into the casing an amount which leaves space—indicated at 47—between the inner edge of the flange and the baffle 35, so as to provide room for substituting a larger size baffle, or one of different configuration.

When the mold liner 12 is removed and replaced by another one having a different size or configuration, the baffle 35 will usually be replaced at the same time by a different baffle that is dimensioned to be compatible with the size or configuration of the substituted mold liner. This is illustrated in FIG. 3 which is a section showing the interior of the casing 10 of FIG. 1 with a curved mold liner 12a and correspondingly curved baffle 35a substituted for the straight mold liner 12 and baffle 35 shown in FIG. 1. Also as seen in FIG. 3, the caps 28 and 29 are replaced by caps 28a and 29a in which the openings through them are appropriately curved to accommodate the curved mold liner 12a. If the size and configuration of the substitute baffle varies considerably from that of the straight shown in FIG. 1, the dimensions of the flange 38 on the baffle may also have to be varied in order for the down-turned edge 40 of the flange 38 to rest squarely on the seal ring 41 on the casing flange 39. However, the width of the seal ring 41, and the manner in which flanges 38 and 39 cooperate, permit quite a bit of latitude so that the dimensions of the flange 38 do not have to be designed with any great degree of precision in order to be able to provide a substitute baffle that will function in the intended manner. As seen in FIG. 3, the portion of the flange 38a at the right of the baffle 35a is slightly wider than at the left to compensate for the curvature of the baffle; the portion of space 47a is also corresponding wider at the right. The only other elements affected by the different configuration of the substitute baffle are the fins 46a which are altered slightly, as indicated in the drawing, to compensate for the curvature of the baffle 35a. The other elements of the mold assembly, namely the casing 10, conduits 21 and 22, flange 39 and seal ring 41, are unaffected and are thus adapted for use with a wide variety of mold liners and baffles of different sizes and configurations.

In operation, the above-described arrangement of the baffle 35 and flanges 38 and 39 forces fluid flowing into the lower chamber 43 from the conduit 16 to circulate down around the lower end of the baffle, up through the space 36 beside the mold liner and then around the upper end of the baffle into the upper chamber 42, from which it flows into the upper conduit 15 and then out through outlet passage 21 in the support. As the fluid thus circulates up through the space 36, it picks up heat from the mold liner 12 to keep the mold cool enough for continuous casting.

It is extremely important that the entire inner surface of the mold liner be cooled below the maximum temperature at which the periphery of molten metal flowing through the mold liner solidifies. If some spot on the mold is too hot, the casting is apt to be imperfect. Therefore, to provide effective cooling it is necessary that the cooling fluid flow up through the space 36 at a substan-

tially uniform rate (preferably provided by a uniform volume at a uniform pressure) around the whole periphery of the mold liner. For this purpose the space 36 is made equal on all sides of the mold liner by the spacer fins 37 and provision is made for introducing the fluid into the chamber 43 and out of the chamber 42 at a substantially equal rate around conduits 15 and 16.

As best seen in FIG. 1, there is only one entry port 20 into the conduit 16 and only one outlet port 19 from the conduit 15. Therefore, to equalize the rate at which fluid enters and exits from the conduits 15 and 16 at all points around the inside of the casing, the several openings 17 and 18 along the respective conduits are made progressively larger the further away they are from the outlet port 19 and inlet port 20.

It is to be understood that the embodiments of the invention shown in the drawings and described in detail are illustrative only and that some modifications and variations may be made in the structure and mode of operation thereof without departing from the scope of the invention defined by the following claims.

What is claimed is:

1. A continuous casting mold assembly comprising: an open-ended casing; a pair of conduits opening into the interior of the casing, means for conducting fluid into one of the conduits and out of the other; including a single entry port opening into the one and a single exit port opening into the other, said openings into the casing along the conduits being of a progressively larger size all along the conduits from points nearest the openings of said ports to the points farthest away for substantially equalizing the flow rate of fluid through the several openings in the respective conduits; a pair of caps attached respectively over the ends of the casing; a tubular open-ended mold liner in the casing with its ends opening through said caps; an open-ended baffle member around the mold liner with a space between; said baffle member being shorter than the interior of the casing between said caps; spacing means for equalizing the width of the space between the mold liner and the interior of the baffle member all the way around them; a first flange projecting inward from around the interior wall of the casing between said conduits; and a second flange around the exterior of the baffle member projecting outward over said first flange and resting thereon to support the baffle member with its ends spaced from the caps and to separate the casing into two members around the baffle member, whereby fluid flowing into one of said chambers from one of said conduits is circulated around the end of the baffle member, through the space between the baffle member and mold liner, into the other of said chambers and then out through the other of said conduits.

of said conduits; said conduits extending entirely around the casing and having openings into the interior of the casing at spaced intervals all along them for, respectively, admitting fluid into and conducting fluid out of the interior of the casing at a substantially uniform rate on all sides thereof, thereby to cause fluid to circulate through the space between the mold liner and baffle member at a substantially equal rate on all sides of the mold liner.

2. A continuous casting mold assembly comprising: an open-ended casing; a pair of conduits openings into the interior of the casing; means for conducting fluid into one of the conduits and out of the other; a pair of caps attached respectively over the ends of the casing; a tubular open-ended mold liner in the casing with its ends opening through said caps; an open-ended baffle member around the mold liner with a space between; said baffle member being shorter than the interior of the casing between said caps; a first flange projecting inward from around the interior wall of the casing between said conduits; and a second flange around the exterior of the baffle member projecting outward over said first flange and resting thereon to support the baffle member with its ends spaced from the caps and to separate the casing into two chambers around the baffle member; a seal ring along the line at which said second flange rests on said first flange, and a plurality of projections spaced apart around an end of the baffle member and extending upward from said end to engage the inside face of the cap over the adjacent end of the casing for pressing said second flange against said seal ring thereby to make a tight fit between the flanges, whereby fluid flowing into one of said chambers from one of said conduits is circulated around the end of the baffle member, through the space between the baffle member and mold liner, into the other of said chambers and then out through the other of said conduits.
